(57) **CLAIM**

The ornamental design for a portable electronic device, as shown and described.

DESCRIPTION

FIG. 1 is a perspective view of a portable electronic device showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof with the waterproof lid lifted;

FIG. 10 is a perspective view thereof showing the portable electronic device in the closed state;

FIG. 11 is another perspective view thereof showing the portable electronic device in the closed state;

FIG. 12 is a perspective view thereof showing the portable electronic device opened to 180 degrees;

FIG. 13 is another perspective view thereof showing the portable electronic device opened to 180 degrees;

FIG. 14 is an enlarged view of the portion, labeled '14' of FIG. 5;

FIG. 15 is an enlarged view of the portion, labeled '15' of FIG. 6; and,

FIG. 16 is an enlarged view of the portion, labeled '16' of FIG. 10.

The even-dash broken lines illustrate portions of the portable electronic device that form no part of the claimed design. The dash-dot broken lines represent the extents of the detail views and form no part thereof.

1 Claim, 15 Drawing Sheets
